[57] CLAIM

The ornamental design for a restaurant building, as
shown and described.

DESCRIPTION

FIG. 1 is a front elevational view of a restaurant building
embodimenting my new design.

FIG. 2 is a side elevational view taken from the right of
the restaurant building shown in FIG. 1, the side view
taken from the left of FIG. 1 being a mirror image of the
right side.

FIG. 3 is a back view of FIG. 1.

FIG. 4 is a top plan view of FIG. 1.
